UNITED STATES PATENT OFFICE.

MATTHIAS LUDLUM, OF FAIR HAVEN, VERMONT.

TRUNK.

Specification of Letters Patent No. 24,648, dated July 5, 1859.

To all whom it may concern:

Be it known that I, MATTHIAS LUDLUM, of Fair Haven, in the county of Rutland and State of Vermont, have invented a new and useful Improvement on Water-Tight Trunks or Boxes for Traveling and other Purposes, of which the following is a full and clear description, reference being had to the accompanying drawing, which forms 10 part of this specification, and in which—

Figure 1 represents a view in perspective of a trunk constructed according to my improvement; Figs. 2 and 3 transverse sections of the same when in its open and closed conditions; and Fig. 4 a longitudinal section through its outer double lid.

The trunk shown in the accompanying drawing has its box or body part (A) made of wood or any other suitable material covered on the exterior with leather (a) and on the interior with a metallic lining (b) covered with cotton (c) or other suitable material. Such construction however may be more or less varied, and the materials 20 changed, so long as said box-part forms a shell that is impervious to water and in a measure or wholly precludes the penetration of damp. A metallic lining, for such purpose or purposes, to boxes of various kinds, 30 has before been used. But, however secure against water and damp, the shell or box part of the trunk may be made, it is of but little or no avail unless the lid or cover be equally secure. Thus, double lids have been 35 employed and variously constructed or fitted to make the lid joint and covering portion equally tight, but seldom, if ever, has this been perfectly attained, or, if so, in an inconvenient or otherwise objectionable manner. A trunk or box of a self sealing character that shall be water and damp proof, 40 or either, at its joints and in or at all its surroundings or parts, including alike the lid and the shell, must ever be a desideratum among travelers and others, and if of buoyant construction as well has its value increased by reason of its applicability to the preservation of valuable contents when the trunk is immersed or thrown into water, 50 and by reason of its adaptability to act as a float for the protection of human life in cases of shipwreck or accident at sea.

My improvement accomplishes this desideratum in a manner more perfect than has 55 heretofore been attained. Thus, I not only construct the box part (A) as specified, but,

employing a freely hung valvular lid or cover (B) within the main or outer lid (C), I also make said valvular lid water and damp proof by facing it on the inside with 60 a metallic lining (d) that may be covered with cotton (e), or otherwise suitably construct the same to give it the same or like water and damp proof character that the box part (A) of the trunk possesses. In 65 other respects this valvular lid (B) need not differ from the valvular lid described in Letters Patent of the United States, issued to me on the fifth day of April, A. D. 1859; said lid being shown as arranged for independent play on the inside of the main or outer lid (C), and being acted upon by a 70 spring (f) and faced or bordered on the inside by leather (g) or other suitable material, so that when the outer lid is shut to 75 said valvular lid accommodates itself in an independent manner to form a water-tight joint to the opening portion of the box, by the leather facing to said valvular lid embedding itself in or on a ledge (h) surrounding the upper part of the shell of the box, and by said valvular lid being forcibly held there by the spring (f) when the outer lid (C) is locked or closed, and, in case of the 80 submersion of the trunk in water and water leaking through the joint or otherwise of the outer lid (C) to the back of the valvular lid, the pressure of the water serving to aid the spring in keeping the valvular lid tight to its fit against its ledge or bed (h). 85

Superior however in many respects as is the valvular lid (B) to a mere leather facing on the inside of the outer lid, a trunk so provided, and metallic lined or made water proof or water and damp proof throughout 90 its box part and valvular lid, would still be insecure and defective, as though the outer lid (C) would protect the valvular lid (B) from external interference or injury and, 95 in the case of strainage or warping of the outer lid, the independently hung and spring borne valvular lid would still accommodate itself to make a close fit at its junction with its ledge or bed (h), yet said valvular lid would be liable to be thrust away from its bed or seat either by an over-packing of the contents in the box or by the weight of the contents resting on the valvular lid in 100 case of the trunk being turned upside down—a likely position for it to assume 105 both when throwing the trunk overboard from a vessel and in the use of it as a float 110

and under a variety of circumstances. Against such, the outer lid (C) offers no protection and however tightly it may be locked it can in no wise control on the inside 5 side the freely hung or independent valvular lid on which the sealing of the box depends. To protect said valvular lid therefore, against inside as well as outside interference, and to secure to it efficiency under every position and variety of circumstances, I make 10 said valvular lid an intermediate one by combining with it and the outer lid an inner lid (D) which may be arranged at or near the top of the box part as supplementary lids to trunks have before been arranged, but the office of which here is, in conjunction with the outer lid, to secure to the valvular lid efficiency of action under every variety of circumstances. Such combination of an 15 independent valvular lid with an inner as well as outer lid is distinguishable from a mere arrangement of supplementary lids.

As the outer lid is provided with a lock or fastening, so the inner lid (D) should also be provided with a hook, spring bolt, or other suitable fastening (S), to secure it when closed.

In illustration of a previous remark that

the mere materials may be changed to give to the trunk its water proof character, I will only add, in conclusion, that, instead for instance of the metallic lining (b and d) to the box part and valvular cover, a composition laid on with the brush may be used; but such and other changes, not materially departing from my improvement as herein set forth, it will be obvious may or may not be adopted.

I claim—

The combination, with a water-tight shell or body part (A) to a trunk or box having ordinary or any other suitable inner and outer lids (C and D), of a valvular spring borne lid (B) of water-tight construction and arranged to occupy an intermediate position in relation to the inner and outer or ordinary lids (C and D), essentially as and for the purpose or purposes herein set forth.

In testimony whereof, I have hereunto 50 subscribed my name.

MATTHIAS LUDLUM.
